VARIABLE DELIVERY ALTERNATING
PISTON PUMPThomas J. Lester, Shaker Heights, Ohio, assignor
to Lester Engineering Company, Cleveland,
Ohio, a corporation of Ohio

Application December 9, 1942, Serial No. 468,370

20 Claims. (Cl. 103—120)

1

The present invention relates to a variable delivery pump, or equivalent power mechanism, of the rotary type and embodying a novel fluid displacement principle in which concentrically rotating elements are caused to have an oscillating movement with respect to each other in order to effect a double acting fluid displacement action. My invention can hence be said to comprise a unique combination of rotary and oscillatory motions.

Prior forms of rotary pumps have required relatively complicated and expensive manufacturing operations, and have necessitated a large number of carefully fitted and precisely made moving parts. Furthermore, in the case of the eccentric rotor, radial piston and movable vane types of rotary pumps, the delivery or displacement action is necessarily limited to one stroke per revolution. In the pump embodying my invention, on the other hand, not only is the structure and manufacture of the moving parts greatly simplified, but also there is obtained a double acting delivery or displacement action in which two delivery strokes for each displacement chamber are accomplished per single revolution.

The pump embodying the principle of my invention includes a rotor of the fixed vane or "wing piston" type which oscillates back and forth in an arcuate chamber or housing, the latter being also in the form of a rotor and concentric with the vane piston rotor. As these two rotors both move through a single revolution and on the same axis, motion is so transmitted from one to the other as to produce a relative acceleration and deceleration therebetween, resulting in a back and forth or oscillatory movement of one rotor with respect to the other during each complete revolution. This transmission of rotary motion is accomplished through the medium of a third rotating element which is mounted upon an axis parallel to, but eccentric to the common axis of the two rotors. Variation in the eccentric position of this third rotating and rotary motion transmitting element in turn produces a variation in the amount of oscillation of one of the rotors with respect to each other, and hence, a variation in the length of the stroke of the vane piston in its chamber, thereby effecting variable delivery control of the pump.

A further object and advantage of my invention is to provide fluid intake and delivery passages through the common axis of the relatively oscillating rotors, together with ports associated with one of the rotors whereby an automatic valving of the intake and delivery strokes of the fluid displacement chambers is achieved.

Another object and advantage of my invention is that the rate of travel of the vane piston in its chamber is substantially of the simple harmonic type, wherein the piston moves relatively slower

2

at each end of its stroke than it does during the mid portion thereof, thus tending to eliminate any sudden impact or hammering action as the piston begins and ends its stroke, thus producing a relatively smooth and even pumping flow. Furthermore, the above-mentioned, automatic valving feature of my invention is so constructed and arranged with respect to this movement characteristic of the vane piston, that the intake and delivery orifices presented by the valve ports are larger and smaller in direct coincidence with the rate of intake and delivery of the pump displacement chamber.

A further object of my invention is to provide a plurality of vane pistons and displacement chambers between the rotating and relatively oscillating rotors, whereby, in addition to the previously mentioned double acting displacement action of an individual vane piston, a plural number of fluid displacement strokes, delivering in sequence, are obtained for each single revolution.

Additional objects and advantages of my invention shall become apparent during the course of the following detailed description.

To the accomplishment of the foregoing and related ends, said invention, then, consists of the means hereinafter fully described and particularly pointed out in the claims, the annexed drawings and the following description setting forth in detail certain means and one mode of carrying out the invention, such disclosed means and mode illustrating, however, but one of various ways in which the principle of the invention may be used.

In said annexed drawings:

35 Fig. 1 is a longitudinal, sectional view taken through a pump embodying the principle of my invention;

Fig. 2 is a sectional view taken substantially along line 2—2 of Fig. 1;

40 Fig. 3 is a detailed, sectional view taken in staggered planes and substantially along line 3—3 as indicated in Fig. 1;

Fig. 4 is an end elevational detail of the vane piston rotor;

45 Fig. 5 is a sectional view taken substantially along line 5—5 of Fig. 4;

Figs. 6—13, incl., are simplified, more or less diagrammatic views illustrating the rotative operation of the major elements of my pump, and 50 showing the parts during one complete revolution, each of said Figs. 6—13, incl., showing such parts at a position of rotation 45° removed from the other; and

Fig. 14 is a geometrical diagram illustrating 55 the principle of my invention.

Now referring more particularly to Figs. 1 and 2 of the drawings, the pump structure shown therein includes an outer housing and frame member 1 of substantially cylindrical shape, with 60 the cover plates 2 and 3 attached thereto, such

as by the cap screws 4. A fixed, hollow shaft 5 is attached to the cover plate 3 by means of the screws 6 engaging with the lateral flange 7 on the left-hand enlarged portion of such fixed shaft. The shaft 5 is hollow and divided by the central partition 8 into an intake passage 9 and a delivery or exhaust passage 10. Pipes or conduits 11 and 12 are connected into the left-hand or outer end of the passages 9 and 10, respectively.

At the right-hand or inner end of the shaft 5, the passages 9 and 10 are opened through the wall of the shaft to the outer surface thereof by means of the removed portions or ports 13 and 14, respectively.

The right-hand end of the shaft 5 is closed and also mounts the male conical pilot bearing 15.

The drive shaft 16 is journaled in the ball bearing 17 which in turn is carried by the cover plate 2. The inner end of the drive shaft 16 has a female, conical pilot bearing 18 fitting over the bearing 15 of the fixed shaft 5; and also carries a flange or plate 19 to which the inner rotor 20 is attached. The rotor 20 carries the rigid, fixed wings or vane pistons 21 which are drilled to receive the cap screws 22 which join the plate 19 on the end of the drive shaft 16 to a similarly shaped plate 23 on the opposite side of the rotor 20. The bolts 22 thus serve as means for clamping the plates 19 and 23 together and also for regulating the pressure with which such plates are held against the radial side faces of the second rotor 24, to seal such meeting surfaces against fluid leakage.

The second rotor 24 surrounds the rotor 20 and is mounted rotatably or oscillatably thereon. The rotor 24 has radially, inwardly directed, fixed abutments 25 which are circumferentially spaced apart a greater arcuate distance than the width of the vane pistons 21, thus forming fluid displacement chambers in which the pistons 21 are adapted to reciprocate.

A pair of ring members 26 and 27 are joined together by the spacer bosses 28, 28 and suitable fastening screws or bolts 29. The rings 26 and 27 have laterally outward projecting hubs 30 and 31, respectively, which are journaled by means of the ball bearings 32 and 33 in the movable housing 35. The housing 35 includes a separable side wall portion 34 which facilitates assembly of the parts. The housing 35 engages the frame housing 1 at the slide bearing surfaces 36 and 37. Adjusting lock bolts 38 and 39 extend through the side of the frame 1 and bear against the bosses 40 and 41, respectively, of the slidable or movable housing 35.

The inner rotor 20 is rotatably connected to the rings 26 and 27 by means of the pivoted link arm 42. The link arm 42 is pivotally connected to the radially projecting portions 19' and 23' of the plates 19 and 23, respectively, and by means of the wrist pin 43. At the other end, the link arm 42 is pivotally connected to the rings 26 and 27 by means of the wrist pin 44.

The outer rotor 24 has a radially projecting portion 24' which in turn is connected by means of the wrist pin 45 to the link arm 46. The latter, it will be noted, is bifurcated to accommodate assembly to the rotor portion 24'. The wrist pin 48, carried by the rings 26 and 27 connects the other end of the link arm 46 to such rings.

The inner rotor 20, as will be noted from Fig. 1, is mounted upon a cylindrical hub portion 20' whose left-hand end is journaled at 47 to the inner, conical bearing on the fixed shaft 5, and

to the outer, ball bearing 49 mounted in the housing wall 3.

By particular reference to Fig. 2, it should be noted that the centers of the wrist pins 43 and 45 are equi-distantly spaced from the common center of rotation of the rotors 20 and 24, which in turn, is the axis of the fixed shaft 5. Also, the centers of wrist pins 44 and 48 are equi-distantly spaced from the center of rotation of the rings 10 26 and 27, and are located at fixed points 180° removed, or diametrically opposite each other, on the rings 26 and 27.

Referring now particularly to Figs. 3, 4 and 5, the inner rotor 20 has a pair of annular passages 15 50 and 51 which are located radially inward from the vane pistons 21. The passage 50 has a port 52 and the passage 51 has a port 53, both of which ports are in radial alignment and communication with the openings 13 and 14 in the fixed shaft 5.

Assuming the rotor 20 to be rotating in a clockwise direction, as shown by the arrow in Fig. 3, communication passages or ports 54 are located just to the rear of the vane pistons 21 and in radial alignment with the annular passage or manifold 50. Ports 55 are located just in advance of the vane pistons 21 and are in communication with the annular passage or manifold 51.

Thus, it will be seen, that as the rotor 20 is in the position as shown in Fig. 3, that fluid enters the intake passage 9, can pass therefrom through the port 52, to the annular manifold 50, through the ports 54 to the space or chamber to the rear of the vane pistons 21. When the rotor 20 is in a position 180° removed from that shown in Fig. 3, or advanced one-half a revolution therefrom, the port 52 is in communication with the delivery passage 10, and similarly are the annular manifold 50 and ports 54 placed in communication with such delivery passage 10. By the same token, the port 53, annular manifold 51, ports 55 and spaces or chambers in advance of the vane pistons 21, placed in communication with the delivery passage 10 when the rotor 20 is in the position of Fig. 3; and in communication with the intake passage 9 when advanced one-half a revolution.

The mode and principle of operation of the above-described invention is clearly illustrated in Figs. 6-13, incl. These figures show the essential elements of the pump, namely, the inner rotor 20, the outer rotor 24, one of the eccentric control rings 26, and the link arms 42 and 46. For the purpose of convenience in illustration, only one and the same vane piston 21 and one and the same abutment 25 are marked with reference numerals in Figs. 6-13, incl. The eccentric ring 26 is shown in these figures moved in a left-hand, horizontal direction so that the eccentricity of the center of the ring 26 is to the left of the common center of the rotors 20 and 24. Thus, the outer dot and dash circle A, passing through the pivot points of the links 42 and 46 on the eccentric ring 26, represents the path of travel of such pivot points; and the inner dot and dash circle B, passing through the points of pivotal attachment of the links 42 and 46 to the rotors 20 and 24, represents the path of travel of the latter pivot points. The parts are assumed to be rotating in a clockwise direction in Figs. 6-13, incl., and each succeeding figure shows these parts in a position 45° of advanced rotation, so that an approximately complete cycle of revolution of 360° is illustrated in all eight figures. As indicated by the legends at the upper left-hand corner of the drawings upon which Figs. 6-13 occur, the fluid which is under pressure or being delivered

from the pump is represented by horizontal, dotted lines, and the fluid being drawn into the pump, viz., the intake, is represented by vertical dotted lines.

Beginning with Fig. 6, the vane piston 21 is just starting upon its delivery stroke, i. e., beginning to move towards the abutment 25. As the rotor 20 is driven in a clockwise direction, the link arm 42, in passing from the position of Fig. 6 to that of Fig. 7, tends to slow down or decelerate the rate of rotation of the ring 26. This slowing down is, in turn, transmitted from the link arm 46 to the rotor 24, to cause the latter to rotate at a slower speed than the rotor 20. Thus, in effect, the link arm 42 can be said to be pulling back on the ring 26, and the link arm 46 pushing back on the rotor 24. The net result is that as the parts rotate through 180°, from the position shown in Fig. 6, to that shown in Fig. 10, the vane piston 21 has traveled from a position furthest removed from the abutment 24 to a position closest to it, thus forcing or displacing the fluid out through the port 55, into the manifold 51, through the port 53, thence to the delivery passage 10.

It will be noted that the movement of the vane piston 21 with respect to the abutment 25 is relatively smaller as it goes from the positions of Figs. 6 and 7 and 9 and 10, than it is in going from the positions of Figs. 7 to 9. This means, of course, that the rate of travel of the piston 21 with respect to the abutment 25 is faster in the mid portion of its stroke than it is adjacent each terminal end. Concurrently with the rotation of the parts in Figs. 6-10, it will be seen that the port 53 has just cleared the end of the baffle wall 8 at the position of Fig. 6 (viz., has just come in registry with the delivery passage 10). In the positions of Figs. 7 and 8, the port 53 has fully cleared the end of the baffle wall 8 and is in completely open and unobstructed position. Then, as the vane piston 21 nears the end of its stroke, the port 53 commences to be closed off by the other side of the baffle wall 8, as shown in Fig. 9 (viz., the port 53 begins to close with respect to the port 14).

As the parts rotate from the position of Fig. 10 to the position of Fig. 13, the link arm 42 tends to push the eccentric ring 26 faster than the rate of rotation of the rotor 20; simultaneously, the link arm 46 tends to pull forward the rotor 24, with the result that the rotor 24 now increases its rate of rotation with respect to the rotor 20, and the vane piston 21 moves away from the abutment 25 and performs its return stroke. Thus, in the positions progressing from Figs. 10-13, the vane piston 21 moves back away from the abutment 25, expanding the displacement chamber therebetween and drawing in the fluid in the port 55 from the manifold 51 through the port 53 from the intake passage 9. The vertical dotted lines, accordingly, indicate the position of the intake fluid.

As also shown in Figs. 10-13, incl., the vane piston 21 moves relatively slower near the terminal ends of its intake stroke than it does during the mid portion thereof; and just as in the case of Figs. 6-10, the port 53, which now becomes an intake port, is partially opened and closed at the beginning and end of the stroke and fully opened during its mid portion.

Although only one individual vane piston 21 and one individual abutment 25 have been referred to in the foregoing explanation in connection with Figs. 6-13, incl., it will be equally well

appreciated that the same operations of delivery and intake are being carried on by all three of the other vane pistons and displacement chambers. In summary, therefore, all four of the vane pistons and displacement chambers are simultaneously taking in and delivering a quantity of fluid during 180° or one-half a revolution of the rotors 20 and 24. As the intake and delivery functions of each displacement chamber are reversed during the next half revolution, viz., from 180° to 360°, the same function occurs, so that in one complete revolution the movement of the vane pistons 21 with respect to the abutments 25 produces two intake strokes and two delivery strokes; so that, in total, during one revolution there occur in the four chambers, eight intake displacements and eight delivery displacements.

Fig. 14 further illustrates the principle of operation of my invention. In this geometric figure, the line CL represents the horizontal center line or plane in which the center O of the eccentric ring 26 and the common center O' of the rotors 20 and 24 are relatively movable. The vertical center line C'L' represents the vertical center line or plane establishing the center O of the eccentric ring 26 and the vertical center line C'L' establishing the common center O' of the rotors 20 and 24. Now, assume a position where the centers O and O' coincide and likewise the center lines C'L' and C'L', and it will be appreciated that, on rotation of the elements 20, 24 and 26, all of them will rotate at equal angular velocities. On the other hand, assume that the center O is moved in a left hand direction with respect to the center O'. In this position the radii R and R', from the center O' to the points of pivotal connection of the link arms 42 and 46, are moved closer toward each other, viz., from 180°, coinciding with the center line C'L' and the center O to a lesser angle, which has here been denoted as 168°, by way of example.

With the centers O and O' in the spaced-apart positions just assumed, the system is now rotated 90° until the link arms take the position as shown by the dotted lines. In this position, it will be seen that the radii R and R' have now increased their angular relationship, viz., to 180°. Then, on rotation to another 90°, the radii R and R' have further increased their angular relationship to 192°. Thus, tabulating the angular relationships of the radii R and R' during a complete revolution of the rotating elements 20, 24 and 26, the following is the result:

Angle of Revolution	Angular relationship of Radii R and R'	
	Degrees	Radians
0°	168	2.93
90°	180	3.14
180°	192	3.33
270°	180	3.14
360°	168	2.93

Therefore, during one complete cycle of revolution, the respective radii R and R' of the rotors 20 and 24 have increased and then decreased in their positions of angular relationship. For the sake of further illustration of this change in angular relationship between the rotors 20 and 24, radial dot and dash lines have been drawn in Figs. 6-13, incl., from the axis of rotation of the rotors 20 and 24 through the centers of the 75 points of pivotal attachment of the link arms 42

and 46 thereto, respectively. It will be noted that the radial line passing through the center of the point of pivotal attachment of the link arm 42 at all times bisects the vane piston 21; and that the radial line passing through the center of the point of pivotal attachment of the link arm 46 at all times bisects the displacement chamber adjacent the abutment 25. Thus, these radial lines in Figs. 6-13, incl., not only represent the relative angular positions of the rotors 20 and 24 during a complete revolution, but also serve as a further measurement of the relative travel or stroke of the vane piston 21 in the displacement chamber. The angle between these radial lines has been denoted by the reference letter C, and by comparing the change in this angle from Fig. 6 through Fig. 13, the relative oscillatory movement between the rotors 20 and 24, as they are both bodily rotating together, will be found exemplified.

It will also be appreciated that the amount of this relative angular change is, in turn, dependent upon, and controlled by the amount of eccentricity of the ring 26 with respect to the rotors 20 and 24, or the distance of the center O from the center O'.

Thus, it will be seen that the characteristic essentials of my invention reside in the provision of a mechanism for transforming uniform velocity rotary motion into variable velocity rotary motion as between rotating elements mounted upon a common axis, whereby such elements are caused to have an oscillatory motion with respect to each other; and that when such mechanism is embodied in a pump or equivalent mechanical engine, the necessity for any addition or extrinsic valve elements or actuating mechanism therefor is eliminated because the rotation of one of the rotary elements with respect to the fixed shaft produces the required valving action for the displacement chambers. The substantial reduction in the number of moving parts of the mechanism of my invention, their simplicity and compactness of construction, and the ease and accuracy of control of the pump stroke and delivery variation are all advantageous features inherent in these general characteristic essentials.

Other modes of applying the principle of the invention may be employed, change being made as regards the details described, provided the features stated in any of the following claims or the equivalent of such be employed.

I therefore particularly point out and distinctly claim as my invention:

1. In a pump, concentric rotary members rotatable with respect to each other, displacement chambers provided between said members, a rotatable member surrounding said rotary members mounted upon an axis eccentric of that of said rotary members, connecting elements between said rotary members and said eccentrically mounted rotatable member for transmitting variable velocity rotary motion from one to the other of said rotary members, said rotary members being in radial alignment, and driving means directly connected to one of said rotary members.

2. In a pump, concentric rotary members rotatable with respect to each other, interfitting abutments on both of said members forming with other portions of the rotary members arcuately shaped displacement chambers, a rotatable member surrounding said rotary members mounted upon an axis eccentric of that of said rotary members, connecting elements between said rotary members and said eccentrically mounted rotat-

able member for transmitting variable velocity rotary motion from one to the other of said rotary members, said rotary members being in radial alignment, and driving means directly connected to one of said rotary members.

3. In a pump, concentric rotary members rotatable with respect to each other, displacement chambers provided between said members, a rotatable member surrounding said rotary members mounted upon an axis eccentric of that of said rotary members, connecting elements between said rotary members and said eccentrically mounted rotatable member for transmitting variable velocity rotary motion from one to the other of said rotary members, means for varying the eccentricity of said rotary member mounted on an axis eccentric whereby to control the relative amount of rotation between said rotary members with respect to each other, said rotary members being in radial alignment, and driving means directly connected to one of said rotary members.

4. In a pump, a pair of concentric rotary members mounted on a common axis and rotatable thereon in unison but with oscillatory motion with respect to each other, a stationary shaft supporting one of said rotary members and a drive shaft directly connected to said one of said rotary members, fixed vane pistons on one of said rotary members and interfitting arcuate displacement chambers therefor carried by the other of said rotary members, intake and eduction passages leading from said chambers to and through said stationary shaft, and rotatable control means surrounding said rotary members and mounted on an axis eccentric to that of said rotary members so connected to said rotary members as to impart said oscillatory motion thereto.

5. In a pump, a pair of rotary members mounted on a common axis, fixedly mounted vane pistons on one of said rotary members and interfitting arcuate displacement chambers therefor carried by the other of said rotary members, a central shaft in said common axis, intake and eduction passages leading from said chambers to and through said shaft, a rotatable member surrounding said rotary members mounted upon an axis eccentric of such common axis, connecting elements between said rotary members and said eccentrically mounted rotatable member for transmitting variable velocity rotary motion from one to the other of said rotary members, said rotary members being in radial alignment, and driving means directly connected to one of said rotary members.

6. In a pump, a pair of rotary members mounted on a common axis, fixedly mounted vane pistons on one of said rotary members and interfitting arcuate displacement chambers therefor carried by the other of said rotary members, a central shaft in said common axis, intake and eduction passages leading from said chambers to and through said shaft, a rotatable member surrounding said rotary members mounted upon an axis eccentric of such common axis, connecting elements between said rotary members and said eccentrically mounted rotatable member for transmitting variable velocity rotary motion from one to the other of said rotary members, means for varying the eccentricity of said rotary member mounted on an axis eccentric whereby to control the relative amount of rotation between said rotary members with respect to each other, said rotary members being in radial alignment, and driving means directly connected to one of said rotary members.

7. In a pump, inner and outer rotary members mounted for rotation on the same axis, a plurality of radially inwardly extending wing pistons fixed on one of said rotary members and a plurality of radially outwardly extending wing pistons on the other, said wing pistons on each of said respective rotary members having circumferential spaces between each other a greater distance than the circumferential width of the individual wing pistons to form displacement chambers between said rotary members, a central shaft in said axis intake and ejection passages leading from the spaces between said wing pistons to said shaft, and motion transmitting means surrounding said rotary member for accelerating and decelerating the rate of rotation of said rotary members with respect to each other and during one revolution of both of said members.

8. In a pump, a pair of rotary members rotatable about a common fixed shaft, displacement chambers in one of said rotary members, and vane pistons operating in said chambers and carried by one of said rotary members an inlet passage and an outlet passage located within said shaft, ports in said shaft and in one of said rotary members in radial alignment with said chambers, said ports communicating said chambers with said passages, and motion transmitting means surrounding and connecting said rotary members for accelerating and decelerating the rate of rotation of one of said rotary members with respect to the other and during one revolution of both of said members.

9. In a pump, a pair of rotary members rotatable about a common fixed shaft, displacement chambers in one of said rotary members, and vane pistons operating in said chambers and carried by one of said rotary members an inlet passage and an outlet passage located within said shaft, ports in said shaft and in one of said rotary members in radial alignment with said chambers, said ports communicating said chambers with said passages, motion transmitting means connecting said rotary members for accelerating and decelerating the rate of rotation of one of said rotary members with respect to the other and during one revolution of both of said members, including a rotatable member surrounding said rotary members mounted upon an axis eccentric of that of said rotary members, connecting elements between said rotary members and said eccentrically mounted rotatable member for transmitting variable velocity rotary motion from one to the other of said rotary members, and means for varying the eccentricity of said rotary member mounted on an axis eccentric whereby to control the relative amount of rotation between said rotary members with respect to each other.

10. In a pump, a pair of rotary members rotatable about a common fixed shaft, a rotatable member surrounding said rotary members and eccentrically mounted, displacement chambers in one of said rotary members, and vane pistons operating in said chambers and carried by one of said rotary members a pair of annular passages in one of said rotary members adjacent said chambers, ports on opposite sides of said vane pistons communicating said chambers with said annular passages, those of said ports on one side of said pistons communicating with one of said annular passages, and those of said ports on the other side of said pistons communicating with the other of said annular passages, an inlet passage and an outlet passage located within said shaft,

said annular passages having openings in communication with said inlet and said outlet passages in said shaft, and connecting elements between said rotary members and said eccentrically mounted rotatable member for transmitting variable velocity rotary motion from one to the other of said rotary members.

11. In a pump, a pair of rotary members rotatable about a common fixed shaft, a rotatable member surrounding said rotary members and eccentrically mounted, displacement chambers in one of said rotary members, and vane pistons operating in said chambers and carried by one of said rotary members a pair of annular passages in one of rotary members adjacent said chambers, ports on opposite sides of said vane pistons communicating said chambers with said annular passages, those of said ports on one side of said pistons communicating with one of said annular passages, and those of said ports on the other side of said pistons communicating with the other of said annular passages, an inlet passage and an outlet passage located within said shaft, said annular passages having openings in communication with said inlet and said outlet passages in said shaft, connecting elements between said rotary members and said eccentrically mounted rotatable member for transmitting variable velocity rotary motion from one to the other of said rotary members, and means for varying the eccentricity of said eccentrically mounted rotary member whereby to control the relative amount of rotation between said rotary members with respect to each other.

12. In a pump, inner and outer rotary members mounted for rotation on the same axis, a plurality of radially inwardly extending wing pistons fixed on one of said rotary members and a plurality of radially outwardly extending wing pistons on the other, said wing pistons on each of said respective rotary members having circumferential spaces between each other a greater distance than the circumferential width of the individual wing pistons to form displacement chambers between said rotary members, a central shaft in said axis intake and ejection passages leading from the spaces between said wing pistons to said shaft, a ring member rotatably and eccentrically mounted surrounding said rotary members, means for directly driving said inner rotary member, a driving connection between said inner rotary member and said ring member, and a driving connection between said ring member and said outer rotary member whereby the latter is rotatably but oscillatably driven with respect to said inner rotary member.

13. In a pump, inner and outer rotary members mounted for rotation on the same axis, a plurality of radially inwardly extending wing pistons fixed on one of said rotary members and a plurality of radially outwardly extending wing pistons on the other, said wing pistons on each of said respective rotary members having circumferential spaces between each other a greater distance than the circumferential width of the individual wing pistons to form displacement chambers between said rotary members, a central shaft in said axis intake and ejection passages leading from the spaces between said wing pistons to said shaft, a ring member rotatably and eccentrically mounted surrounding said rotary members, means for directly driving said inner rotary member, a driving connection between said inner rotary member and said ring member, a driving connection between said ring member and said outer rotary member whereby the latter is rotatably but oscillatably driven with respect to said inner rotary member.

11

outer rotary member whereby the latter is rotatably but oscillatably driven with respect to said inner rotary member, and means for varying the eccentricity of said ring member with respect to the axis of rotation of said rotary members to control the extent of such oscillating movement.

14. In a pump, a rotary member having a plurality of radially projecting vane pistons fixed thereon, a second rotary member enclosing said rotary member and having arcuately shaped chambers receiving said pistons, a fixed shaft supporting both said rotary members, an inlet passage and an outlet passage located within said shaft, a pair of annular passages in one of said rotary members adjacent said chambers, ports on opposite sides of said vane pistons communicating said chambers with said annular passages, those of said ports on one side of said pistons communicating with one of said annular passages, and those of said ports on the other side of said pistons communicating with the other of said passages, said annular passages having openings in communication with said inlet and said outlet passages in said shaft, and motion transmitting means surrounding and connecting said rotary members for accelerating and decelerating the rate of rotation of one of said rotary members with respect to the other and during one revolution of both of said members.

15. In a pump, a rotary member having a plurality of radially projecting vane pistons fixed thereon, a second rotary member enclosing said rotary member and having arcuately shaped chambers receiving said pistons, a fixed shaft supporting both said rotary members, an inlet passage and an outlet passage located within said shaft, a pair of annular passages in one of said rotary members adjacent said chambers, ports on opposite sides of said vane pistons communicating said chambers with said annular passages, those of said ports on one side of said pistons communicating with one of said annular passages, and those of said ports on the other side of said pistons communicating with the other of said passages, said annular passages having openings in communication with said inlet and said outlet passages in said shaft, a ring member rotatably and eccentrically mounted surrounding said rotary members, means for directly driving said rotary member, a connecting link between said rotary member and said ring member, a connecting link between said ring member and said second rotary member whereby the latter is rotatably but oscillatably driven with respect to said rotary member.

16. In a pump, a rotary member having a plurality of radially projecting vane pistons fixed thereon, a second rotary member enclosing said rotary member and having arcuately shaped chambers receiving said pistons, a fixed shaft supporting both said rotary members, an inlet passage and an outlet passage located within said shaft, a pair of annular passages in one of said rotary members adjacent said chambers, ports on opposite sides of said vane pistons communicating said chambers with said annular passages, those of said ports on one side of said pistons communicating with one of said annular passages, and those of said ports on the other side of said pistons communicating with the other of said passages, said annular passages having openings in communication with said inlet and said outlet passages in said shaft, a ring member rotatably and eccentrically mounted surrounding said rotary members, means for directly driving

12

said rotary member, a connecting link between said rotary member and said ring member, a connecting link between said ring member and said second rotary member whereby the latter is rotatably but oscillatably driven with respect to said rotary member, and means for varying the eccentricity of said ring member with respect to the axis of said fixed shaft to control the extent of such oscillatory movement of said rotary housing.

17. In a pump, a rotary member having a plurality of radially projecting vane pistons fixed thereon, a second rotary member enclosing said rotary member and having arcuately shaped chambers receiving said pistons, a fixed shaft supporting both said rotary members, an inlet passage and an outlet passage located within said shaft, a pair of annular passages in one of said rotary members adjacent said chambers, ports on opposite sides of said vane pistons communicating said chambers with said annular passages, those of said ports on one side of said pistons communicating with one of said annular passages, and those of said ports on the other side of said pistons communicating with the other of said passages, said annular passages having openings in communication with said inlet and said outlet passages in said shaft, a ring member rotatably and eccentrically mounted surrounding said rotary members, means for directly driving said rotary member, a connecting link between said rotary member and said ring member, a connecting link between said ring member and said second rotary member whereby the latter is rotatably but oscillatably driven with respect to said rotary member, a bearing housing rotatably supporting and enclosing said ring member, said bearing housing being laterally movable with respect to said fixed shaft, and means for so moving said bearing housing to vary the amount of eccentricity of said ring member and thereby to control the extent of such oscillatory movement of said rotary housing.

18. In a pump, a pair of concentrically mounted rotors, a plurality of fixed vane pistons carried by one of said rotors, arcuately shaped displacement chambers for said pistons carried by the other of said rotors, a rotatable ring member mounted adjacent said rotors, and link arms pivotally connecting each of said rotors, respectively, to said ring member, said link arms each being in radial alignment with one of said rotors.

19. In a pump, a pair of concentrically mounted rotors, a plurality of fixed vane pistons carried by one of said rotors, arcuately shaped displacement chambers for said pistons carried by the other of said rotors, a drive shaft directly connected to one of said rotors, a rotatable ring member mounted adjacent said rotors, and link arms pivotally connecting each of said rotors, respectively, to said ring member, said link arms each being in radial alignment with one of said rotors.

20. In a pump, a supporting housing, a pair of rotors concentrically journalled in said housing, a plurality of vane pistons fixedly carried by one of said rotors, arcuately shaped displacement chambers for said pistons carried by the other of said rotors, a second housing movably mounted within said supporting housing in a direction transverse to the axis of said rotors, a ring member rotatably journalled in said second housing with its axis of rotation parallel to the axis of said rotors, link arms pivotally connecting each of said rotors, respectively, to said ring member,

13

conduit means at the axis of rotation of said rotors for introducing and educting fluid to be pumped to and from said displacement chambers, and means for directly driving said one of said rotors carrying said vane pistons.

THOMAS J. LESTER.
